HAND DISPENSER FOR TAPE OR THE LIKE

Ernest Loeb, Berwyn, Ill.

Application May 9, 1955, Serial No. 35,881

Term of patent 14 years

(Cl. D74—1)

Fig. 3

Fig. 2

Fig. 1

Fig. 6

Fig. 5

Fig. 4

Fig. 1 is a bottom plan view of a hand dispenser for tape or the like showing my new design;

Fig. 2 is an end view thereof;

Fig. 3 is a top plan view;

Fig. 4 is a side elevational view thereof;

Fig. 5 is an end view showing the end opposite to that shown in Fig. 2; and

Fig. 6 is an elevational view of the side opposite to that shown in Fig. 4.

The roll of tape shown in dotted lines in Figs. 4 and 6 is for illustrative purposes only.

I claim:

The ornamental design for a hand dispenser for tape or the like, as shown and described.
